UNITED STATES PATENT OFFICE

MARTIN KRUMM, OF COLUMBUS, OHIO.

DESIGN FOR IRON FENCES.

Specification forming part of Design No. **6,373**, dated January 28, 1873.

To all whom it may concern:

Be it known that I, MARTIN KRUMM, of Columbus, in the county of Franklin and State of Ohio, have invented a new and original Design for a Fence, of which the following is a specification:

The accompanying photograph fully illustrates my new design.

This invention relates to a new design for metallic fence-posts, pickets, and rails, and to a new combination of the same with each other.

Each post is made of flat bar-iron of the form shown—that is to say, of a bifurcated support, contracting neck, and halberd-shaped point or top.

Each picket is made spear-shaped, and has pear-like enlargements under and over the top and middle rails, respectively, as shown. These two rails are made in continuous semicircles, between which the pickets pierce them.

I claim as my invention—

1. The design for a fence-post having a bifurcated support or base, contracted neck or upper portion, and a halberd-shaped top, as shown.
2. The design for a fence-picket having a spear-shaped point and pear-shaped enlargements, as shown.
3. The design for the fence-rail formed of a series of semicircles joined, as shown.
4. The design for a fence composed of the post, the picket, and the rails, each having the particular form shown and above indicated.

MARTIN KRUMM.
